UNITED STATES PATENT OFFICE.

MARSHALL TILDEN, OF WILLIMANTIC, CONNECTICUT.

SPOOL.

No. 872,480.

Specification of Letters Patent.

Patented Dec. 3, 1907.

Application filed March 2, 1906. Serial No. 303,816.

To all whom it may concern:

Be it known that I, MARSHALL TILDEN, a citizen of the United States, residing at Willimantic, in the county of Windham and State of Connecticut, have invented a certain new and useful Improvement in Spools, which improvement is fully described in the following specification, reference being also made to the accompanying drawings.

10 The chief aim of this invention is to improve that class of spools in which the barrel or body portion is formed by rolling up a ribbon of paper, or the like material; said ribbon being so pasted or glued as to form, 15 when finished, a solid, and practically homogeneous structure, as is clearly described in Patent No. 611,343, issued to me September 27th 1898.

My present invention seeks to produce a 20 spool, or the barrel portion of a spool, formed of a piece of paper wound a plural number of times upon itself, thus producing a tube, or spool body, having slitted ends that may be readily expanded and secured by wedging, 25 or otherwise, in separately formed heads.

In order to explain my said invention clearly I have provided the annexed sheet of drawings, in which

Figure 1 is a view of a short section of a 30 ribbon of paper suitably formed to carry into effect my present invention. Figs. 2 and 3 are, respectively, side and end views of a spool body formed of said ribbon, and Fig. 4 is a view of a finished spool. Fig. 5 shows 35 said spool partly in central, longitudinal, section in order to disclose one method of securing the flanged head to the cylindrical body of the spool. Fig. 6 is an end view of the spool shown in Fig. 5. In Figs. 7 and 8 40 I have illustrated, partly in section, modified means for securing the spool head to the body; these modifications having particularly in view to provide a spool in which the slitted ends of the spool body will be concealed from view.

In these drawings the letter *a* indicates a 45 ribbon of paper, or the like material, which is to be pasted and coiled upon itself to produce a stiff and cheap spool body, and *a'* designates slits in one or both of the edge portions of said ribbon, said slits being located with mathematical precision, and in such relation to each other that, when the paper is coiled upon itself two or more times, certain pre-determined slits or narrow openings will re-

sult in the finished cylindrical structure at its end portions. The same result may be attained by slitting said tube or spool body after it is formed, but I preferably slit the ribbon as described. This construction provides a body portion having longitudinally extending, laminated, flexible, tongues at each end of the said body.

As I have already stated, the heads of the spool of this present invention are made 60 separately from the body and said heads (indicated by the letter *b*) may be made of turned wood or compressed pulp, with a central opening whose inner end will just receive the spool body and whose outer end is somewhat 65 greater in diameter, in order that the slitted end portions of said body may be securely locked in the head by wedging, as I will describe, referring now to the form of spool shown in Fig. 5 of the drawings. The body 70 *a* is first slipped into the head until the free, slitted, end of said body is flush with the outer face of the head and, preferably, the body is glued before thus entering it in the head. A slightly tapering bushing *c*, of wood 75 or other suitable material, is then forced into the otherwise open end of the body, thus expanding the slitted portion and clamping it firmly to the head. This construction provides a spool whose ends appear as seen in 80 Fig. 6.

If it is desired to further protect, and hide from view, the slits *a'* the outer end of the bushing *c* may be formed with a definite enlargement or flange *c'* at its extreme outer 90 end, as seen in Fig. 8, that fills the central opening in the spool head; in which case the outer end of the slitted body would be slightly counterbored, or compressed, so as to form a knife edge at said outer end (see Fig. 8), 95 or the bushing may be shortened, as in Fig. 7, leaving room for the insertion of a disk *d* that will fill the opening in the end of the head and thus insure a neat appearance to the spool end.

The improved method of forming spools described by me in this present specification provides a completed structure of great strength, at very small cost, and of extreme lightness.

Having thus described my invention I claim as new and wish to secure by Letters Patent:—

1. A spool body comprising a strip of paper coiled a number of times upon itself and hav-

100

ing slits in the ends of each coil which register with slits in the ends of the other coils of said body.

2. In a spool, a body portion comprising a strip of paper coiled a number of times upon itself and having slits in the ends of each coil which register with slits in the ends of the other coils in combination with heads secured to the slitted body.

10 3. In a spool, a body portion comprising a strip of paper coiled a number of times upon itself and having slits in the ends of each coil which register with slits in the ends of the other coils in combination with heads secured to the slitted ends, and means consisting of a tapered bushing for securing the said body in said heads all being substantially as specified.

15 4. In a spool, a body portion comprising a strip of paper coiled a number of times upon

itself and having slits in the ends of each coil which register with slits in the ends of the other coils in combination with heads secured to said slitted body, and means for covering the otherwise exposed slitted ends 25 of the body.

5. In a spool, a body portion comprising a strip of paper coiled a number of times upon itself and having slits in the ends of each coil which register with slits in the ends of the other coils in combination with a head secured to said slitted portion, a bushing in said body, and means for covering the otherwise exposed slitted ends of the body consisting of disks inserted in the said heads.

MARSHALL TILDEN.
